United States Patent

Des. 236,826
Patented Sept. 16, 1975

236,826

IDENTIFICATION LABEL

Arthur L. Smith, 3507 Rosehedge Drive,
Fullerton, Calif. 92635

Filed Nov. 1, 1973, Ser. No. 411,784

Term of patent 14 years

Int. Cl. D19—08

U.S. Cl. D19—13

FIG. 1 is a perspective view of an identification label showing my new design, the indicia and cable being shown in broken lines for illustrative purposes only;

FIG. 2 is a side elevational view of the identification label;

FIG. 3 is a plan view of the identification label;

FIG. 4 is an end view of the label showing the channel design of the indicia encapsulating member; and

FIG. 5 is an enlarged cross-sectional view of the identification label taken along lines 5—5 of FIG. 2.

I claim:

The ornamental design for an identification label, as shown and described.
